PHONOGRAPH RECORD

Benjamin H. Shuemaker, Eureka, Calif.

Application November 8, 1940, Serial No. 364,920

1 Claim. (Cl. 274—42)

This invention relates to phonograph records.

An object of this invention is to provide a phonograph record which is formed as a combined article of novelty and utility.

Another object of this invention is to provide a phonograph record which is formed with a wooden body or base and a composition coating enclosing the body or base, the composition being of such a character that recording grooves may readily be cut thereinto and the tonal vibrations retained in the grooves of the composition coating.

Another object of this invention is to provide a phonograph record of this kind which is formed with a wooden body or base and a substantially transparent coating which is adapted to receive and retain the recording grooves.

A further object of this invention is to provide a phonograph record of this kind which is adapted to be formed out of wood which is indigenous to a particular locality and which is also pleasing in appearance, the wood being preferably of the type known as burl and the coating about the body is of a transparent characteristic so as to not only display the burl in the wood fibers in addition to the coloring of the wood, but also to act as a preservative for the wood.

A still further object of this invention is to provide an improved method of forming a phonograph record which includes the initial cutting of a disc-shaped body and the dipping of the body for a number of times into a transparent coating solution which is so formed that it will readily retain a recording groove and permit the transmission of the recording on a conventional phonograph.

A further object of this invention is to provide a phonograph record of this kind which will not readily break and which is provided with a coating which will not readily burn, the coating being of such a characteristic as to permit the formation of the disc-shaped body as a very thin element, the coating acting to hold the body against splitting and the entire structure being very light in weight so that it may be easily shipped through the mails without danger of breakage.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to

which fall within the scope of the invention as claimed.

In the drawing:

Figure 1 is a detail plan view of a phonograph record constructed according to an embodiment of this invention.

Figure 2 is an enlarged fragmentary sectional view taken on the line 2—2 of Figure 1.

Figure 3 is a fragmentary plan view of the wooden body before it is coated.

Referring to the drawing, the numeral 10 designates generally a disc-shaped phonograph record constructed according to an embodiment of this invention. The record 10 comprises a disc-shaped body 11 which is formed out of burl wood such as redwood, maple or pepperwood burl. The body 11 is formed of a particular kind of wood which is representative of a particular geographic location and is designed as a display means in the form of a souvenir which may be purchased and retained for an indefinite period.

The body 11 after being cut in disc shape is formed with a central opening 13 for receiving the spindle of a phonograph machine and the body 11 may also be formed with a second opening 12 which is offset from the opening 13. The opening 12 may be provided for the purpose of receiving an offset pin which is carried by a recording instrument so that the disc member 11 will be held against rotation relative to the rotating recording table of the recording instrument.

In order to provide a means whereby the opposite faces and also the marginal edge portions of the body 11 may be coated in order to permit the cutting of a recording groove therein, I have provided a transparent coating 14 which is of initially liquid form and in which the body 11 is initially dipped. The coating 14 not only engages the opposite faces of the body 11, but as shown in Figure 2 at 15, the coating 14 engages about the outer marginal edge portion of the body 11. The coating which is applied to the body 11 is preferably formed of a mixture of cellulose, lacquer or acetate and beeswax. The cellulose and lacquer are mixed together in equal parts and beeswax is added in the proportion of 10% of the entire composition. The body 11 is preferably dipped into a fluid mixture of these elements and in order to provide the desired thickness of the composition, the body 11 is dipped into the coating material a number of times, the coating material being permitted to thoroughly dry after each dipping. The coating material will not only be absorbed into the fibers of the body 11, but

will also form a very smooth and transparent surface on opposite faces of the body 11.

After the body 11 has been dipped into the coating solution a sufficient number of times to provide the desired depth of coating, the completed blank phonograph record is placed on a recording machine and a recording groove 16 is cut into either one or both faces of the coating material which encloses or encompasses the disc-shaped body 11. Due to the composition of the coating material being a cellulosic base, the coating will readily retain the recording groove and the recording track may be formed simultaneous with the cutting of the groove 16. After the desired recording groove and track has been formed in one or more faces of the coating material, the record 10 may be placed on a phonograph with the spindle projecting through the central hole 13.

It will be understood that the body 11 may be of such thin construction that it might warp slightly but due to the light construction of the body 11 and the coating 14 thereon, this unevenness in the body 11 will not materially affect the character of the recording impressed on one or more faces of the record.

Preferably the wood from which the body 11 is made is of a knotty or burl configuration so as to thereby provide a pleasing or artistic structure which will be characteristic of the particular geographic location from which the article is purchased.

The coating material 14 is relatively tough in composition when dried so that this coating material will provide a reinforcing means for the wooden body 11.

The body 11 may be made out of redwood, maple, pepperwood or other fine grained wood which has highly conspicuous configurations thereon so that the body 11 will form an attractive article which is very light in construction and will withstand exceedingly hard usage. It is well known that ordinary composition phonograph records will quickly break when dropped whereas a phonograph record constructed according to this invention will withstand hard shocks and will thus last indefinitely.

The coating 14 gives the appearance of a varnished coating for the body 11 and at places where the record groove 16 is not cut into the coating 14, the outer surface of the coating 14 is of high gloss.

What I claim is:

A phonograph record comprising an integral composite body formed of a disc-like inner section of burl wood, and a relatively thick transparent outer section completely enclosing the inner section and formed from an initially liquid subsequently stiffened composition of cellulose lacquer and beeswax, said outer section possessing a characteristic to receive and retain the sound tracks.

BENJAMIN H. SHUEMAKER.
